UNITED STATES PATENT OFFICE.

CHARLES A. HORN, OF WOODHAVEN, NEW YORK, ASSIGNOR OF ONE-FOURTH TO W. EVERITT RUNDLE, OF EAST ORANGE, NEW JERSEY, AND ONE-FOURTH TO HAROLD E. LOMBARD, OF BLOOMFIELD, NEW JERSEY.

STEAM-SUPERHEATER.

1,379,409.

Specification of Letters Patent.

Patented May 24, 1921.

Application filed September 18, 1919. Serial No. 323,508.

To all whom it may concern:

Be it known that I, CHARLES A. HORN, a citizen of the German Republic, residing at Woodhaven, in the county of Queens, city and State of New York, have invented certain new and useful Improvements in Steam-Superheaters, of which the following is a full, clear, and exact description.

This invention relates to steam superheaters, and its chief object is to provide a superheater in which the tubes are internally braced or reinforced to resist sagging or bending, to enable long tubes to be used without the employment of objectionable intermediate supports in the path of the hot gases. Another object is to provide an internally reinforced superheater in which the reinforcing structure provides a plurality of passages in each tube, through which the steam flows in succession, thus permitting the use of tubes of large diameter with high steam velocity therethrough. A further object is to provide a superheater in which the steam passages decrease in length as the steam approaches the outlet of the superheater, thus securing a substantially uniform velocity throughout. To these and other ends the invention consists in the novel features and combinations hereinafter described.

A convenient and effective embodiment of the invention is illustrated in the accompanying drawings, in which:

Fig. 1 is a sectional view showing one complete superheater section or unit.

Fig. 2 is a cross section of one of the tubes, on line 2—2 of Fig. 1.

Fig. 3 is a sectional plan view on line 3—3 of Fig. 1.

Fig. 4 is a longitudinal section through one tube and part of the header, showing a modification.

Fig. 5 is a cross section on line 5—5 of Fig. 4.

Fig. 6 is a longitudinal section through one tube and part of the header, showing another modification.

Fig. 7 is a cross section on line 7—7 of Fig. 6.

In its preferred form the superheater comprises a series of tubes 20, each closed at its outer end and connected at its inner end, preferably by welding, to a header 21, provided at its ends with an inlet nozzle 22 and

an outlet nozzle 23, suitably arranged. The 55 tubes are provided inside with combined baffles and reinforcing members 24, extending from the outer wall of the header (to which they may be welded) to a point near the outer end of the tube. The baffles or 60 partitions fit the sides of the headers and the inner surface of the tubes closely, thus dividing each tube into two (or more) passages. The steam, entering the first tube, flows out through one passage to the 65 end of the tube, then back through the other passage to the header; then out and back through the next tube, and so on through the tubes in succession, as indicated by the arrows in Fig. 1, finally 70 emerging from the outlet 23. Each tube is therefore in effect two tubes, and hence I am able to use tubes of larger diameter and proportionately greater stiffness, at the same 75 time obtaining the advantages of smaller tubes as regards steam velocity and heat transference. Preferably the partitions or baffles are twisted, as shown, so that the steam is forced to take a helical or screw-path. This gives a radial component of 80 motion to the steam, tending to throw the steam radially outward against the surface of the tubes. This effect is very marked at high steam velocity, and materially increases the rapidity of heat transference from the 85 furnace gases to the steam.

It is important that the partitions fit the tubes tightly, preferably by a driving fit, so as to be in firm contact with the tubes throughout. This facilitates conduction of 90 heat to the baffles and thus makes the latter an effective part of the heating surface; and by eliminating or minimizing relative motion between the tube and the baffle, it enables the latter to serve as an inner truss, 95 so stiffening the tube as to practically prevent sagging under high temperatures. I am therefore able to use longer tubes, without intermediate supports between their ends, and can subject the superheater to 100 higher temperatures, without risk of the injurious distortion so frequently encountered in prior apparatus.

As the steam flows through the superheater its temperature, and hence its volume per 105 unit weight, increases. I therefore progressively increase the pitch of the partitions from the inlet to the outlet, the first

partition having the greatest number of turns and the last having the least number, as clearly indicated in Fig. 1. This gives a fairly uniform velocity throughout and makes the several tubes equally efficient.

The twisted or screw-type partition has another important advantage, in that the passages are intertwined, in effect mixing the two currents of steam together. This 10 equalizes the temperature of the tube and its partition, and practically prevents the unequal expansion, and consequent injurious distortion, that sometimes results when the two currents are confined to separate 15 sides of the tube or are caused to flow outwardly through one tube and back to the header through another tube.

The partition may be of uniform cross section, but I prefer to provide it with a 20 central longitudinal stiffening rod or bead, as indicated at 25.

A two-blade baffle or partition as in Figs. 1 and 2, is usually adequate, but three or more blades may be used if desired. Figs. 25 4 and 5 illustrate a four-blade construction, 24^a, providing two ingoing channels, *a* and *b*, and two outgoing channels, *c* and *d*. Figs. 6 and 7 show a four-blade construction in which the partition, 24^b, is straight instead 30 of being twisted. This gives the highly advantageous truss effect for stiffening the tubes but does not take care of unequal expansion due to difference in temperature of the ingoing and outgoing steam.

35 As made up for use with a steam boiler the complete superheater usually consists of two or more sections such as are described above, each section or unit consisting of a header and two or more tubes.

40 It is to be understood that the invention is not limited to the specific constructions herein illustrated and described but can be embodied in other forms without departure from its spirit.

45 I claim:

1. In a steam superheater, two tubes through which the steam flows in succession, and each having a twisted or helical parti-

tion to provide helical steam passages, the pitch of the partition in the second tube being greater than the first, and means serially connecting said tubes. 50

2. A steam superheater comprising in combination, a header having inlet and outlet openings, a plurality of superheating tubes connected thereto, and a plurality of twisted or helical partitions extending through the respective tubes to divide each of the latter into a plurality of helical steam passages, the pitch of said partitions increasing from the inlet to the outlet. 55

3. In a steam superheater, a header, a plurality of tubes connected at one end to the header and closed at the other end, and a plurality of twisted or helical partitions extending across the header and into the tubes to a point near the outer end of the latter, dividing the tubes into a plurality of helical ingoing and helical outgoing passages communicating through the header, the partitions at the outlet of the header having fewer turns than the partitions at the inlet. 60

4. A steam superheater comprising in combination, a tube having a substantially uniform cross-section, a second tube having a substantially uniform cross-sectional area, on a plane at right angles to the tube axis, substantially equal to the internal cross-sectional area of the first tube on a similar plane, means in said first tube, and in conjunction with the inner wall of said first tube, forming a steam passage of greater length than said first tube but of lesser effective cross-sectional area than the first 75 named cross-section, means in said second tube and, in conjunction with the inner wall of said second tube, forming a steam passage of greater length than said second tube but of greater effective cross-sectional area 80 than the effective cross-sectional area of the first mentioned passage, and means serially connecting said passages. 85

In testimony whereof I hereunto affix my signature.

CHARLES A. HORN.
